UNITED STATES PATENT OFFICE.

WILLIAM J. FABIAN, OF EVANSTON, ILLINOIS.

CALCULATING-MACHINE.

1,265,440.

Specification of Letters Patent.

Patented May 7, 1918.

Application filed May 21, 1915. Serial No. 29,517.

To all whom it may concern:

Be it known that I, WILLIAM J. FABIAN, a citizen of the United States, and resident of Evanston, county of Cook, and State of Illinois, have invented certain new and useful Improvements in Calculating-Machines, of which the following is a specification, and which are illustrated in the accompanying drawings, forming a part thereof.

10 The invention relates to machines for making arithmetical computations and more particularly to those having provision for printing the items and the result of the computation from the same type. The object of 15 the invention is to provide a calculating machine which shall be of simple construction and capable of performing a variety of operations with a minimum of manual manipulation.

20 In the accompanying drawings,

Figure 1 is a plan view showing a calculating machine embodying the features of improvement provided by the invention,

25 Fig. 2 is a longitudinal vertical sectional view of the same taken on two planes indicated by the broken line 2—2 on Fig. 3,

Fig. 3 is a plan sectional view taken on the line 3—3 of Fig. 2,

30 Fig. 4 is a plan view of the machine with the cover removed and with the side walls of the case and the stems of certain of the controlling keys shown in section, some parts being omitted for simplicity of illustration,

35 Fig. 5 is a detail front elevation with the parts of the case and certain of the operating elements shown in section and with some of the parts broken away,

40 Fig. 6 is a side elevation showing one of the accumulator wheels,

Fig. 7 shows an intermediate supporting frame and some parts of the mechanism adjacent thereto in side elevation, a pair of operating shafts and a detail of the case being 45 shown in section,

Fig. 8 is a detail view of the key-board and some of the associated members, partly in section,

Fig. 9 is a detail rear elevation of the mechanism within the case, a part of the floor plate being shown in section,

Fig. 10 is a detail side elevation showing some of the controlling elements of the mechanism, the supporting shafts therefor and a part of the case being shown in section,

Figs. 11 and 12 are detail views of the item wheels and some of the supporting members, Fig. 11 being partly in section on the line 11—11 of Fig. 12, and Fig. 12 being partly in section on the line 12—12 of Fig. 11,

Figs. 13, 14 and 15 are detail side views drawn to an enlarged scale and showing the construction of different portions of the rims of the main wheel segments employed in the machine, some of the parts being broken away in Figs. 14 and 15,

Fig. 16 is a detail side view showing the parts employed for supporting and operating two of the platens against which the printing is accomplished, with a detail of the floor plate appearing in section, and

Fig. 17 is a front elevation showing the manner in which the apparatus provided by the invention may be associated with a type-writing machine for permitting the conjoint use of the two machines for billing and the like.

In the particular form of construction selected for illustration the operative parts are principally inclosed within a case generally designated 50 and comprising a floor plate 51, front and rear end walls 52, 53, the two side walls 54, and 55, and a cover plate 56. The floor plate 51 is represented as being provided with a recess 57 for the reception of the platen roller 58 of an ordinary typewriting machine. A well known form of typewriting machine is shown in outline at 59 in Fig. 17.

When the calculating machine provided by the invention is to be used in conjunction with a typewriting machine, as 59, a stand 60 is desirably employed. As shown the stand is provided with seats 61 and 62 for

supporting the typewriting machine 59 and the case 50 of the calculating machine in suitable relative positions for the endwise movement of the platen 58 of the typewriting machine into the recess 57 of the floor plate 51 from one side of the case 50. A pair of main side frames 63 and 64, a pair of intermediate frames 65 and 66 and a pair of brackets 67 and 68, all rising from the floor plate 51, provide the principal supports for the parts within the case 50.

In addition to having provision for printing both the items and results of the computations against the platen, as 58, of a typewriting machine, the apparatus preferably also includes means for printing the items and results upon two record strips, as 69 and 70. These record strips turn over the platens which are shown at 71 and 72, respectively, and both of which are supported outside of the case 50, as by the extension of the brackets 67 and 68 through an opening 73 in the rear wall 53. The platen 71 extends between and is directly supported by the brackets 67 and 68. The platen 72, on the other hand, is mounted between a pair of crank arms 74 and 75 of a rock shaft 76, which in turn, extends between and is journaled adjacent its opposite ends in the brackets 67 and 68.

The record strips 69 and 70 may be supplied from any convenient source. In the arrangement shown, the record strip 70 is supplied to the platen 72 from a spool 77. This spool is removably journaled between the outer end portions of the brackets 67 and 68. The machine is also supplied with a set of item wheels 78 and accumulator wheels 79, both of which are visible through openings, as 80 and 81, in the front wall 52. The actuation of the machine may be accomplished from an operating handle 82 which is exposed at one side of the case 50. At each operation of the machine this handle is manually swung downwardly and forwardly. As the handle is idle during its return movements, the movement of the handle in this direction is conveniently accomplished by a spring, as 291. (See Fig. 3.)

The drawings show the machine equipped with eighty-one numeral keys 83. These are arranged in nine rows, as 84, 85, 86, 87, 88, 89, 90, 91 and 92. A blank key 93, for correcting errors, is associated with each of the said rows of numeral keys 83. To provide for the operation of the machine for accomplishing several different results there is also a plurality of controlling keys 94, 95, 96, and 97. These last mentioned keys are conveniently marked to indicate the character of the operation for which they are provided. As shown, the key 94 is marked "R" for repeat, the key 95 "T" for total,

the key 96 "ST" for subtotal and the key 97 "S" for subtract.

All of the keys 83 and 93 have stems marked 100 and 100^a respectively. These key stems slide vertically through the cover plate 56 and through a supplemental plate 70 112 which is supported below and spaced apart from the cover plate 56, as by brackets 111. A separate elevating spring 98 is associated with each of the numeral keys 83 and blank keys 93. As shown, each elevating 75 spring 98, reacts between the under side of the cover plate 56 and a stud 99 which is fixed in the stem, as 100 or 100^a, of the corresponding key.

The stems, as 101, 102, 103 and 104 of the 80 controlling keys 94, 95, 96 and 97 also slide through the cover plate 56. Each of these key stems extends downwardly through the chamber of the case 50, in front of the supplemental plate 112, and telescopically enters the bore of a tubular guide lug 105. The guide lugs 105 are all formed upon a common bracket plate 106 which is secured against the floor plate 51 of the case. A spring 107 is housed within the bore of each 90 of the tubular guide lugs 105 and reacts between the floor plate 51 and the lower end of the corresponding key stem 101, 102, 103 or 104 for elevating the corresponding key. 95

A latch mechanism for retaining each of the numeral keys 83 in depressed position and for preventing the depression of a second numeral key 83 in any of the rows 84 to 92, is desirably provided. To this end an 100 oscillating channeled locking plate 108, rotated in one direction by a spring, as 290, is associated with each of the said rows of numeral keys. These locking plates extend between and have their opposite ends pivotally mounted in bars 109, 110 (Fig. 2). The bars 109 and 110 extend transversely beneath the cover plate 56 in front of all of the numeral keys 83 and in rear of the blank keys 93, respectively. They are supported by being secured against the brackets 111. 105 110

The stem 100 of each of the numeral keys 83 has a plurality of lateral notches 113, 114 and 115, (Fig. 7). The notches 113, 115 are of the same depth. The notch 113 is so formed as to provide the key stem with an oblique downwardly facing cam shoulder 116. Similarly, the notch 114 serves to provide the key stem with upwardly and downwardly facing abrupt shoulders 117 and 118, the notch being deeper adjacent the downwardly facing shoulder 118 than adjacent the upwardly facing shoulder 117. The notch 115 is so formed as to provide 125 the key stem with an abrupt downwardly facing shoulder 119.

Upon the depression of a numeral key 83

in any row, the oblique downwardly facing cam shoulder 116 of the stem of the depressed key engages the lower edge 120 of the corresponding locking plate 108 and 5 swings the locking plate upon its axis to bring the upper edge, as 121 of the locking plate into engagement with the downwardly facing abrupt shoulder 118 of the stem 100 of each of the remaining numeral 10 keys in the same row. The depression of a second key in the same row without first depressing the corresponding blank key, 93, is accordingly prevented. As the oblique cam shoulder 116 of the stem of the depressed key passes below the lower edge 120 of the locking plate 118, the spring rotation of the plate causes this edge to be engaged with the upwardly facing abrupt shoulder 117 for holding the key 15 20 in depressed position but without disengaging the upper edge 121 of the locking plate 108 from the downwardly facing shoulders 118 of the remaining key stems 100 in the same row.

25 When a numeral key 83 in any row has been improperly depressed, it is elevated and the subsequent depression of any numeral key 83 in the same row is permitted by pressing the corresponding blank key 30 93. For this purpose a pair of lateral notches 122 and 123 are formed in the stem 100^a of each blank key 93. Each notch 123 is so formed as to provide the corresponding key stem 100^a with an oblique downwardly 35 facing cam shoulder 124. Upon the depression of the blank key 93, the oblique cam shoulder 124 of its stem 100^a, engages with the lower edge 120 of the corresponding locking plate 108 and swings the locking 40 plate upon its pivots to disengage the said lower edge 120 of the plate from the upwardly facing shoulder 117 of the stem 100 of any depressed key 83 in the same row. The depressed numeral key is accordingly 45 elevated by its spring 98 and upon the release of the blank key 93, the locking plate 108 is rotated by its spring to disengage the upper edge 121 of the plate from the downwardly facing shoulders 118 of the 50 stems of the remaining numeral keys in the same row.

Separate sets of type, generally designated 125, 126, and 127, respectively, are preferably employed for printing against 5 the platens 58, 71 and 72. The type of each set comprises nine rows of ten characters each and the ten characters in the corresponding rows of all of the sets are mounted for simultaneous movement. As shown, nine wheel segments designated, 128, 129, 130, 131, 132, 133, 134, 135, and 135^a, are provided for supporting the type. These wheel segments are mounted for rotation about a common axis as by being pivotally

supported in alinement on a transverse 65 shaft 136. This shaft has its opposite ends journaled in the side frames 63 and 64.

Each wheel segment 128 to 135^a is formed with rim sections 137, 138, and 139 upon which the corresponding type of the three 70 sets 125, 126, and 127 are respectively mounted. A fourth rim section 140 formed upon each of the wheel segments 128 to 135^a serves for carrying a set of sliding pins 141 and a set of yielding gear teeth 142. Each 75 rim section 140 is carried by an arm 143 and the arms 143 of the several wheel segments are laterally offset in differing amounts. This arrangement permits the several rows of characters in each of the 80 sets of type 125, 126, and 127 to move in planes which are relatively close together while the sliding pins 141 and pawls 142 of the several wheel segments are more widely separated. The spacing of the pins 85 141 of the several wheel segments 128 to 135^a is thereby arranged to correspond with the spacing of the several rows 84 to 92 of the numeral keys 83.

In the operation of the machine, selected 90 characters from the several sets of type 125, 126, and 127 are brought to printing position in front of the corresponding platens 58, 71, and 72, by angular movement of the wheel segments 128 to 135^a. 95 Normally each of these wheel segments occupies a position in which the zero characters 144, 196, and 197, of the three sets of type 125, 126, and 127, are positioned in front of the corresponding platens. Accidental displacement of each wheel segment, as 128, from this position is prevented by providing the rim section 139 of each segment with a notch 145 which is yieldingly engaged by a leaf spring 146 100 (Fig. 2.) This leaf spring 146 is conveniently supported by being secured against the under side of a tie rod 147 which extends between and connects the side frames 63 and 64.

Movement of the wheel segments 128 to 135^a, is accomplished by a selective depression of the pins 141, and the engagement of a movable actuating arm 148 with the depressed pins. As shown, the numeral keys 110 115 83 serve for depressing the pins 141 into the path of the actuating arm 148. The pins 141 upon each wheel segment 128 to 135^a are accordingly alined with the lower ends of the stems 100 of the keys 83 in one of the 120 rows 84 to 92. For supporting the pins 141, the adjacent part of the rim section 140 of each wheel segment, as 128 is composed of a pair of parallel plates 149, 150 (Fig. 15) which are laterally spaced apart to slidably 125 receive the pins 141 between them. This relative position of the plates 149, 150 is maintained by means of a plurality of spac-

ing blocks 151 which unite the marginal portions of the plates, between the pins 141. Each pin 141 is held against accidental displacement in each of its two positions by 5 locating an expansion spring 152 in the space inclosed by the side plates 149 and spacing blocks 151, alternately between each two adjacent pins. Two notches 153 and 154 are provided upon each pin for engagement with 10 the corresponding spring 152 in the two positions of the pin. Preferably the pins 141 have T-heads 155. These heads limit the downward movement of the pins and overhang the side of the corresponding wheel 15 segment, as 128 for engagement with a movable restoring bar 156.

The restoring bar 156 is movably held against one side of the rim section 140 of the corresponding wheel segment, as 128. As 20 shown, the two ends of the restoring bar 156 are respectively united with a swinging link 157 and with a lever 158, both of which are in turn pivotally secured against the adjacent side plate, as 150, of the corresponding 25 rim section 140. The lever 158 extends rearwardly beyond the end of rim section 140 of the corresponding wheel segment, as 128, and into the path of the stem 100^a of one of the blank keys 93. Depression of a blank key 30 93 accordingly serves to restore any depressed pin 141 of the corresponding wheel segment, as 128, in addition to performing the function already described of permitting the restoration of any depressed numeral key 35 83, in the same row, as 84.

Upon each forward movement of the actuating arm 148, each wheel segment 128 to 135^a, upon which a pin 141 has been depressed, is moved through a sufficient distance to bring the depressed pin against a 40 fixed stop rod 159, (Fig. 4). The wheel segments are then firmly held against movement by the engagement of the depressed pins 141 between the actuating arm 148 and 45 the stop rod 159 while printing is accomplished from the type 125, 126 and 127. The stop rod 159 extends transversely through the wheel segments 128 to 135^a below their rim sections 140 and in rear of arms 143. 50 The stop rod is supported at its opposite ends upon the said frames 63 and 64. It serves to limit the return movement of the wheel segments 128 to 135^a by engagement of the arms 143 with said rod.

55 The actuating arm 148 extends between and is rigidly supported at its opposite ends upon a pair of crank arms 160 and 161. These crank arms are fixed upon the shaft 136, each crank arm being located just inside of the corresponding side frame 63, 64. The rotation of the shaft 136 for swinging the crank arms 161 and moving the actuating arm 148 is one of the operations accomplished upon the forward movement of the 60 operating handle 82. As shown, this operat-

ing handle is provided with a tubular hub formed in two sections, 162 and 163. These hub sections are rotatably connected by providing the outer section, as 162 with studs 164 which enter notches formed in the adjacent end of the inner section, as 163. Both of the tubular hub sections 162, 163 of the operating handle 82 are supported by being sleeved upon a fixed stud 166. This stud has one end fixed in the intermediate frame 70 member 66. It projects outwardly therefrom through the side frame 64 and the adjacent side wall 55 of the case 50. The hub section 162 extends loosely through the adjacent side wall 55 of the case and through 80 the side frame 64, in the latter of which it has a bearing to provide an additional support for the operating handle.

Movement of the operating handle 82 is transmitted to a train of gears 167, 168, 169, 85 170, 171 and 172. These gears are all of uniform size and each is turned through one complete revolution at each operation of the machine. The gear 167 is fixed upon a shaft 173 (Fig. 9). This shaft extends through 90 the intermediate frames 63 and 66, with each end of the shaft projecting somewhat beyond the adjacent frame member. The gears 168 and 169 and 171 are idle gears serving merely to transmit motion 95 to other gears in the train. Each is accordingly journaled upon a stub shaft, as 174, which is supported upon and projects inwardly from the intermediate frame member 66. The gear 170 is fixed upon a cam 100 shaft 175 which extends through and is journaled in all of the frame members 63, 64, 65, 66.

The cam shaft 175 is supplied with a cam 182 for turning the shaft 136 to swing the 105 actuating arm 148. As shown, a crank arm 183 is formed integral with the crank arm 161 and projects below the shaft 136. This crank arm carries a cam roller 184 for cooperating with the cam 182. The gear 172 is 110 fixed upon a cam shaft 176. The cam shaft 176 extends between and is journaled in the frame members 63 and 66 beyond the forward end of the frame member 65, (Fig. 3).

The means provided for transmitting 115 movement from the operating handle 82 to the gear 167 comprises a curved gear segment 177 (Fig. 2) and a pinion 178 (Fig. 9). The gear segment 177 is formed integral 120 with the inner hub section 163 of the operating handle 82. The pinion 178 is loosely mounted on the shaft 173 and meshes with the gear segment 177 at all times. This pinion is so proportioned in size with reference to the length of the gear segment 177 125 that the pinion is turned through an angular distance slightly in excess of one complete revolution at each movement of the operating handle. The rotation of the pinion 178 during the forward movement of the op- 130

erating handle 82 is communicated to the shaft 173 through the operation of a pawl 179 (Fig. 9), carried by the pinion, and a ratchet disk 180 fixed upon the shaft 173 adjacent the pinion and having a single ratchet tooth 181. The movement of the pinion 178 in excess of one revolution insures that the pawl 179 will pass over the ratchet tooth 181 of the disk 180 during the 10 return stroke of the operating handle 82.

In order that the shaft 173 shall be brought to rest in a definite position at the completion of one revolution after the engagement of the pawl 179 with the ratchet tooth 181, a suitable stop mechanism is desirably provided. As shown, the ratchet disk 180 is formed with an annular enlargement 209 (Fig. 9). This enlarged portion of the disk 180 is provided with a radially projecting stop lug 210. The stop lug 210 is so positioned as to be engaged with a lateral projecting stop lug 211 formed on the gear segment 177 at the completion of the forward stroke of the operating handle 82.

To insure that the operations of the machine shall proceed in their proper order, provision is preferably made for preventing any return movement of the operating handle 82, except upon the completion of its forward stroke. As shown, a stationary ratchet bar 185 (Fig. 4) having forwardly facing ratchet teeth, is secured against the frame member 64 upon the inside. This 30 ratchet bar co-operates with a pawl arm 186. For this purpose the pawl arm 186 is formed with a laterally projecting head 187 having a downwardly and forwardly facing oblique cam surface 188 (Fig. 2). The pawl arm 40 186 is connected with a crank arm 189 which swings with the operating handle 82. As shown the crank arm 189 is provided with a hub 190 which fits upon the outer hub section 162 of the operating handle 82 and is secured thereto in angularly adjusted position, as by a set screw 191 (Fig. 3).

When the parts are in the position of rest (illustrated in Fig. 2), the head 187 of the pawl arm 186 is located beyond the rear end of the ratchet bar 185 and rests upon a horizontal shelf 192 which is formed upon the side of the frame member 64. A leaf spring 193 is secured against the under side of the ratchet bar 185 and normally extends 50 downwardly and rearwardly therefrom to a point beyond the rear end of the ratchet bar 185. At the beginning of the forward stroke of the operating handle 82, the oblique cam surface 188 of the head 187 of the pawl arm 60 186 is engaged with the rear end of the leaf spring 193 and the pawl arm is thereupon lifted by a cam action to a position above the ratchet bar 185. The forwardly facing teeth of the ratchet bar 185 accordingly prevent any return movement of the operating

handle 82 until the head 187 of the pawl arm 186 has passed beyond the forward end of the ratchet bar. The pawl arm 186 then falls to a position in which its head rests upon the horizontal shelf 192. During the 70 return movement of the operating handle 82, the head 187 slides upon the shelf 192 and moves under the ratchet bar 185, the leaf spring 193 yielding upwardly to permit the head of the pawl arm to pass.

In the arrangement shown, printing from the sets of type 125 and 126 is accomplished by the operation of hammers 194 and 195, respectively, against the type which are aligned with the corresponding platen 58 or 75 121. The type characters, as 196, (Fig. 14) of these sets are accordingly mounted for movement in the direction of their length. For this purpose the corresponding rim section, as 138, of each of the wheel segments 80 128 to 135^a is formed from a pair of laterally separated parallel plates 198, 199, between which the type character, as 196, is slidingly mounted. Springs, as 200, insure the return of the type characters after each 90 movement of the corresponding hammers, as 195. These springs are conveniently located between the two side plates 198 and 199 of which the corresponding rim section, as 138, is composed. As shown, a spacing 95 block 201 is fixed in position between the side plates, as 198 and 199 in front of the spring and the spring reacts between this block and a laterally projecting shoulder 202, formed upon the corresponding type 100 character, as 196.

The hammers 194 and 195 are arranged in sets, each set including a number of hammers equal to the number of wheel segments 128 to 135^a. The hammers 195 are slidingly 105 mounted for lengthwise movement in a horizontal plane. As most clearly shown in Fig. 9, these hammers slide in ways 203, formed in a bar 204. The bar 204 is supported by being secured against the under 110 side of a tie rod 205 which connects the intermediate frame members 65 and 66. The operative stroke of each hammer is accomplished by a separate spring, as 206 (Fig. 2). As shown the springs 206 are formed from 115 flat strip metal folded to substantially a U-shape. Each spring 206 reacts between the forward edge of the tie rod 205 and a shoulder 207 formed on the corresponding hammer.

The retraction of the printing hammers 195 is accomplished by a cam 208 (Figs. 2 and 9). This cam is fixed upon the shaft 173 and is preferably made wide enough to be operable upon all of the hammers of the 125 set. As shown, each hammer 195 is provided with a downturned end portion 212 which is so formed as to provide a shoulder 213 for engagement with the cam 208. A recessed portion 214 extending entirely 130

across the face of the cam 208 provides for the release of all of the hammers 195 at the same time.

As it is preferable that zeros should not be printed at the left of the first figure of any item or total, provision is made for restraining the movement of the hammers 194 and 195 which are in alinement with the wheel segment, as 128 from which no printing is to be accomplished. For this purpose the downturned end portion 212 of each hammer 195 is extended beyond the cam engaging shoulder 213 to a position in which it is normally alined with the upturned hooked end portion 215 of a swinging lever 216. A separate one of the levers 216 (Fig. 9) is provided for coöperating with each hammer 195. These levers are pivotally supported upon a rod 217 which extends between and is carried by the intermediate frame members 65, 66. A spring 218 is provided for yieldingly supporting the upturned hooked end portion 215 of each lever in elevated position. As shown, each spring 218 has one end connected with a tie rod 219 which extends between the intermediate frame members 65, 66, below the rod 217. The other end of each spring 218 is connected with a forwardly directed arm 220 of one of the corresponding levers 216.

When printing is to be accomplished from a type character, as 196 of any one of the wheel segments 128 to 135^a, the corresponding lever 216 is depressed to free the downturned rear end portion 212 of the corresponding hammer 195. In the arrangement shown, printing is always accomplished from the type of any wheel segment 128 to 135^a which has been rotated by the forward movement of the actuating arm 148. Furthermore, when but one column of figures is to be printed, zeros should be printed from those wheel segments which have not been moved but which are located at the right of any wheel segment which has been moved, as viewed in Fig. 3. A cam shoulder 221, formed on each wheel segment 128 to 135^a, serves for depressing the corresponding lever 216 against the effort of its spring 218 to release the corresponding hammers 194 and 195 when the wheel segment is rotated. As shown, each lever 216 is provided with an upstanding arm 222 and this arm carries a roller 223 for engagement with the cam shoulder 221 of the corresponding wheel segment 128 to 135^a.

The printing of zeros against the platen 71 from wheel segments 128 to 135^a which have not been rotated, is accomplished by securing a rigid leaf 224 or 225 against the under side of each of the levers 216 in such manner that it will extend beneath the next adjacent lever to the right, as viewed in Fig. 9. When but one column of figures is to be printed, depression of any lever

216 accordingly serves to depress all of the remaining levers to the left, as viewed in Fig. 9, to permit the operation of the corresponding hammers 194 or 195.

To permit the printing of more than one column of figures provision is made for interrupting the transmission of movement between the levers 216 through the overlapping leaves 224, 225. As shown, one of the leaves, as 225, is downwardly offset and is only actuated upon the depression of the next adjacent lever 216 to the right, as viewed in Fig. 9, through an intermediate movable block 226. The action of the levers 216 at one side of the leaf 224 to depress the levers which are at its other side, is accordingly interrupted by withdrawing the movable block 226 from between the downwardly offset portion of said leaf and the under side of the next adjacent lever to the right (Fig. 9). To this end the movable block 226 has a socketed rear end portion 227 and is supported by the telescopic engagement of this socketed end portion with the upper end of an upright arm 228 of a bell crank lever 229. The bell crank lever 229 is pivotally supported upon the floor plate 51 of the case 50. The other arm, as 230, of this lever serves as a handle for withdrawing the block 226 and extends horizontally rearward through an opening 231 in the wall 53 to a conveniently accessible position in rear of the case. If desired, the arm 230 of the bell crank lever 229 may be constructed to yieldingly pass over a shoulder 232 formed in the margin of the opening 231, in its downward movement to be engaged with said shoulder for holding the movable block 226 in retracted position until released.

The printing hammers 194 (Fig. 2) are swingingly mounted. As shown they are pivotally supported in alinement upon a tie rod 233 which extends between the intermediate frame members 65, 66, just above the adjacent rim sections 137 of the wheel segments 128 to 135^a. Springs 234 are provided for swinging these hammers in the direction of their operative movement. The hammers 194 are moved in the other direction by a cam 235. The cam 235 is mounted upon the cam shaft 175 and is of sufficient width to be operable upon all of the hammers 194. The springs 234 have one end connected with a rod 236, Fig. 3, which projects laterally inward from the intermediate frame 65 in the direction of but not reaching to the intermediate frame member 66. The other end of each spring 234 is operatively connected with a forwardly projecting arm 237 of one of the hammers 194. Each hammer 194 is also provided with an upstanding arm 238 so formed as to provide a shoulder 239 for engagement with the cam 235 and to extend upwardly and rearwardly

105

110

115

120

125

130

beyond said shoulder to a position above said cam shaft 175. An arm, as 240, formed integral with each lever 216 extends forwardly therefrom and is normally located 5 in alinement with the end of the upstanding arm 238 of one of the hammers 194. The swinging of the levers 216 accordingly serves to control the operation of the hammers 194 in the same manner as the hammers 195.

To provide against the printing of zeros from the type 127, at the left of the first number of any item or total, the zero characters, as 144 of the type are each movably mounted upon the rim section 139 of the corresponding wheel segment 128 to 135* and their position is also controlled by the swinging of the levers 216. As shown, each zero character, as 144 is formed with a laterally offset base portion 246, which is pivotally secured against the side of the corresponding rim section 139, as at 247 (Fig. 13). A spring 241 reacts upon each of these type characters to withhold it from the printing position. A set of bell crank levers 242 are pivotally mounted in alinement with the central shaft 136 and each serves to advance one of the zero type characters 144 when it is required that it should print. As 20 shown one of the arms, as 243, of each bell crank lever 242 is movable against the under side of the corresponding zero character 144. The other arm, as 244 of each bell crank lever 242 is engaged with the arm 240 of one of the levers 216. To insure that movement of each lever 216 in both directions will be imparted to the bell crank lever 242, the arm 240 is provided with a finger 245 which projects upwardly over the 25 adjacent end of the arm 244 of the bell crank lever 242.

The printing movement of the platen 72 toward the type 127 is accomplished by one 45 of the cams, as 248, of a cam block 260 (Figs. 9 and 16). This cam block is fixed upon the shaft 173 at one side of the intermediate frame member 65. The cam 248 is operable against a cam roller 249 for shifting a link 250 upon which the roller 249 is mounted. The link 250 is in turn operatively connected with a crank arm 251 of the rock shaft 76. For guiding the movement of the link 250 its forward end is bifurcated as at 252 (Fig. 16) and this bifurcated end 50 of the link straddles the shank of a headed stud 253 which is formed upon the end of the cam block 260. A spring 254 reacting between the crank arm 251, and a fixed part of the frame, as the standard 67, serves for 55 holding the roller 249 in engagement with the cam 248 and accomplishing the return movement of the platen 72 away from the type 127.

Rotation of the platen 72 for advancing 60 the strip of paper, as 70, thereover, may be

accomplished upon the return of the platen to its normal position of rest illustrated in Fig. 16. As shown, a bell crank lever 255 is pivotally secured against the side of one of the crank arms, as 74, which supports the 70 platen. One arm of this bell crank lever carries a spring pawl 256 for coöperating with the feeding ratchet 257 of the platen. The other arm of the bell crank lever 255 coöperates with a fixed cam lug 258 which is 75 formed integral with the standard 67 above the rock shaft 76. Upon the forward movement of the platen 72 toward the type 127 the bell crank lever 255 becomes disengaged from the cam lug 258 and the pawl 256 is 80 retracted. As the platen 72 reaches the limit of its return movement, the bell crank lever 255 is again engaged with the cam 258, and the pawl 256 is advanced for rotating the platen.

The rotation of the platen 71 for feeding the strip of paper, as 69 thereover, is conveniently accomplished by a cam 259. As shown, this cam is mounted on the shaft 173, as by being formed upon the same cam 90 block 260 with the cam 248. The cam 259 operates against one end of a lever 261 which is pivotally secured against one side of the standard 67. A spring pawl 262 is mounted upon the other end of the lever 261 for coöperating with the feeding ratchet 263 of the platen 71. A spring 264 reacts between the lever 261 and the standard 67 for withdrawing the pawl 62 from engagement with the feeding ratchet 263, and holding 100 the lever in engagement with the cam 259.

The yielding gear teeth or pawls 142 with which each wheel segment 128 to 135* is provided serve for rotating the item wheels 78 and the accumulator wheels 79 (Fig. 2). 105 The pawls 142 of each set are pivotally secured against the rim section 140 of the corresponding wheel segment, as by set screws 265. The movement of each pawl in one direction is limited by a stop pin 266 110 which is fixed in the rim section 140 adjacent the pawl. The pawls are yieldingly held against these stop pins, as by means of springs 267 which react between each two adjacent pawls.

The item wheels 78 are rotated in one direction only by the corresponding yielding gear teeth or pawls 142. A spring 268 (Fig. 12) is accordingly employed for rotating each of these wheels in the opposite direction. As shown, the item wheels 78 are arranged in alinement upon a fixed shaft 269 which extends between the side frames 63, 64, adjacent the sight openings 80 in the front wall 52 of the case. Spacing collars 125 270, alternating with the item wheels 78, are fixed upon the shaft 269. Coöperating stop lugs 271 and 272, Fig. 11, formed on each item wheel 78 and the adjacent spacing collar 270 serve to prevent further rotation 130

of the item wheels 78 in one direction, when the zero characters, as 273, are in register with the sight openings 80. Each spring 268 is coiled about the hub of the corresponding item wheel 78 and reacts between the item wheel and the adjacent spacing collar 270 for turning the wheel to bring the stop lug 271 against the stop lug 272.

The accumulator wheels 79 are loosely mounted upon a shaft 277 which extends between the side frames 63, 64, adjacent the sight openings 81 in the front wall 52 of the case. Each of these wheels is conveniently made of such size as to comprise two sets of numerals 274, 275, Fig. 5, and a corresponding number of gear teeth 276 Fig. 6. Carrying mechanism for advancing each accumulator wheel 79 through an angular distance corresponding to the spacing of its gear teeth 276, when the next wheel to the right, as viewed in Fig. 5, completes a half revolution of movement, is accordingly required. As shown, star wheels 278, one meshing with the gear teeth 276 of each of the accumulator wheels 79 except the last one to the right, as viewed in Fig. 5, are employed. These star wheels are loosely mounted upon a shaft 279 which has its opposite ends supported in bracket lugs 280 formed on the side frames 63 and 64. Each star wheel 278 is made wide enough to engage with the gear teeth 276 of the corresponding wheel 79 and to project beyond the adjacent side of the same. A pair of diametrically opposed studs 281 and 282 are fixed in each wheel 79, except the last one to the left, as viewed in Fig. 5, for engaging the adjacent star wheel 279 at each half revolution of the accumulator wheel in which they are respectively mounted.

The yielding gear teeth 142 with which the wheel segments 128 to 135^a are supplied, provide that the item wheels 78 and accumulator wheels 79 are turned during the rotation of the several wheel segments to the left, as viewed in Fig. 2. When the accumulator wheels are supplied with the form of carrying mechanism shown, it is required that they be rotated successively beginning at the right, as viewed in Fig. 5. As the actuating arm 148 serves to simultaneously advance all of the wheel segments 128 to 135^a upon which pins 141 have been depressed, it is accordingly provided that these wheel segments are returned one at a time.

A cam shaft 283 having a plurality of cam arms 284 serves for effecting the return movement of the wheel segments 128 to 135^a. The cam arms 284 are arranged along the shaft 283 and are angularly spaced apart thereon for successive engagement with the wheel segments 128 to 135^a. The cam shaft 283 preferably extends from the intermediate frame 65 through the in-

termediate frame 68 to the side frame 64 and is journaled in all three of these frame members.

For rotating the cam shaft 283 a pinion 285 is mounted thereon and this pinion 70 meshes with an intermediate gear 286. The intermediate gear 286 is rotatably supported against the side frame member 64 and meshes with a driving gear 287. This driving gear 287 is rotated through one fourth 75 of a revolution at each movement of the operating handle 82, such motion occurring near the completion of the forward movement of the handle. As shown, the driving gear 287 is fixed upon a shaft 288. This 80 shaft extends between the intermediate frame 68 and adjacent side frame 64 and the two ends of the shaft are journaled in said frames.

Motion is communicated to the shaft 288 85 and driving gear 287 from the cam shaft 175. For this purpose a star wheel mechanism, illustrated in Fig. 7, is employed. This star wheel mechanism includes a pair of disks 289 and 290 of different size. These 90 disks are preferably formed integral and they are mounted on the cam shaft 175. The star wheel, as 291, is mounted on the shaft 288 and has a plurality of radial sockets 292 and intermediate curved surfaces 95 293. A stud 294 projects laterally from the larger one, as 289, of the two disks 289, 290 for entering the socket 292 of the star wheel 291 to turn the same. The rim of the smaller disk 290 is normally engaged with 100 one of the curved surfaces 293 of the star wheel 291 to hold the same against movement but is provided with a notch 295 to permit the turning of the star wheel during 105 that part of each revolution of the shaft 175 105 when the stud 294 is engaged with one of the sockets 292.

The clearing of the item wheels 78 preferably occurs at the beginning of each operative movement of the handle 82. For 110 this purpose it is only necessary to release the pawls 142 from engagement with the item wheels 78, the rotation of the wheels being then accomplished by the springs 268. The release of the pawls 142 is effected by 115 means of shoes 298, one operating against the rear end portions of the pawls 142 of each wheel segment 128 to 135^a in line with the corresponding item wheel 78. As shown a crank shaft 296 (Fig. 4) extends between 120 the side frames 63, 64, over the item wheels 78. This crank shaft carries a plurality of crank arms 297 one of which extends inwardly adjacent the rim section 140 of each of the wheel segments 128 to 135^a. Each of 125 the crank arms 297 carries one of the shoes 298 upon its free end. A cam 299 carried by the cam shaft 175 adjacent the remote end of said shaft from the cam 182 serves to swing the crank shaft 296 for advancing the 130

shoes 298. As shown, a three-armed lever 300 is pivotally mounted on the shaft 136 adjacent the cam 299. One arm of this lever is supplied with a cam roller 301 for engagement with said cam. Another arm of the lever 300 is connected with a crank arm 302 of the crank shaft 296, as by a link 303. A projection 304 (Fig. 10) formed on the cam 299 serves for swinging the lever 300 at the beginning of each rotation of the cam shaft 175.

Preferably the same movement of the three-armed lever 300 which permits the clearing of the item wheels 78 also serves 15 to permit the restoration of the numeral keys 83. As shown, a sliding bar 305 extends transversely below the rear end portion of the cover plate 56 for simultaneously rotating all of the locking plates 108, Fig. 8.

20 The bar 305 is provided with an upstanding lug 306 for engaging each of the locking plates 108. The bar 305 is conveniently supported by having its opposite ends slidingly connected with bracket lugs, as 307, 25 which rise from the supplemental plate 112. An arm 308 projects downwardly from the sliding bar 305 through a slotted opening in the supplemental plate 112 and into the path of a cam 309 which is carried by an oscillating bar 310. The oscillating bar 310 extends transversely through the machine over the rear end portions of the pin restoring levers 158 (Fig. 2). The opposite ends of the oscillating bar 310 are connected to a 30 rock shaft 311, as by crank arms 312. The rock shaft is rotated by movement of the three-armed lever 300 (Fig. 10) and a link 313 which serves for connecting one of the crank arms 312 with one of the arms of the 35 lever 300.

40 While an upward movement of the oscillating bar 310 serves to permit the restoration of the numeral keys 83, a downward movement of this same bar serves to swing the levers 158 for restoring the pins 141. This last mentioned movement of the oscillating bar 310 normally occurs just prior to the completion of each operative movement of the handle 82 and is conveniently accomplished by a spring 314 (Fig. 10). The spring 314 acts upon the lever 300 to hold the roller 301 against the cam 299. A depression 315, formed in the rim of the cam 299, permits the spring 314 to swing the lever 300 through a sufficient distance for effecting the restoration of the pins 141.

45 When it is desired that an item once set up by the numeral keys 83 should be repeated during successive movements of the 60 operating handle 82, the restoration of the pins 141 is prevented. This is accomplished by the depression of the repeating key 94, (Fig. 1). Downward movement of the stem 101 of this key serves to swing a stop arm 65 316 (Fig. 10) into the path of a lug 317

formed on one of the arms of the lever 300 to prevent the movement of the lever 300 by the spring 314 for the entrance of the cam roller 301 into the depression 315 of the cam.

70 The stop arm 316 is preferably constructed in the form of one of the crank arms of a tubular rock shaft 316^a. This rock shaft is pivotally supported upon a stud 318 which projects inwardly from the adjacent 75 side frame 63. When so constructed a bracket lug 319 formed on the tubular rock shaft 316^a serves to provide an anchor for the spring 314. This bracket lug is so positioned on the rock shaft 316^a that the 80 spring 314 serves the additional function of normally holding the stop arm 316 out of the path of the lug 317. A link 320 extends forwardly from another crank arm, as 318^a of the rock shaft 316^a. The forward end of 85 this link is connected with one of the crank arms 321 of a second tubular rock shaft 321^a. This rock shaft is also supported upon a stud, as 322 which projects inwardly from the side frame 63. A lug 323, carried by another crank arm, as 322^a of the rock shaft 321^a, extends into the path of a cam 324. This cam is carried by the stem 101 of the 90 repeating key 94.

95 A latch mechanism is preferably provided for holding the key 94 in depressed position. As shown, a spring advanced latch bolt 325 slidably extends through the front wall 52 of the case and is provided with a push button 326 at its forward end. The rear end 100 of the latch bolt 325 is formed into an eye 327 for receiving the key stem 101 and one wall of this eye is made chamfered to form a detent 328 for engagement with a notch 329, in the stem 101. In order that the pins 105 141 may be automatically restored after any operation of the machine has been repeated the desired number of times, the push button 326 is preferably depressed to release the key 94 before swinging the handle 82 for 110 the last one of said operations. Should the depression of the push button 326 be omitted, and the repetition of operations be thereby completed without restoring the depressed pins 141, it will be necessary to depress the blank key 93 which is associated 115 with each row, as 84 to 91, from which numeral keys 83 have been depressed, to obtain the restoration of the depressed pins 141 before a new operation of the machine 120 may be begun.

125 The subtraction of items is accomplished by reversely rotating the accumulator wheels 79. For this purpose a set of intermediate or subtraction pinions 332, capable of actuation by the yielding gear teeth or pawls 142 of the wheel segments 128 to 135^a, are provided. These subtraction pinions also serve for holding the accumulator wheels 79 against accidental movement. As shown, 130

each subtraction pinion 332 is so positioned as to be engaged with the gear teeth 276 of the corresponding accumulator wheel 79 at all times, but is normally located at one side of the path of movement of the yielding gear teeth or pawls 142 of the corresponding wheel segment 128 to 135^a. To this end, the subtraction pinions 332 are mounted in alinement upon a longitudinally movable shaft 333. A pair of collars 334, 335, fixed upon the shaft 333 adjacent its opposite ends, serve to insure the axial movement of the pinions 332 with the shaft in both directions. The shaft 333 extends between and is slidably journaled in the side frames 63 and 64. One of the collars, as 335, is provided with an annular groove 336, and this groove is entered by one of the crank arms, as 337, of a rock shaft 338. The rock shaft 338 is supported by being journaled in a bracket 339, (Fig. 2), which is secured against the side frame 64. Another crank arm, as 340, of the rock shaft 338 extends into the path of a stud 341 which is mounted on the stem 104 of the subtraction key 97. Depression of the subtraction key 97 accordingly serves to move the shaft 333 in one direction. A spring 342 reacts between the crank arm 337 and the side frame 64 for moving the shaft 333 in the other direction.

For holding the accumulator wheels 79 against accidental movement, the subtraction pinions 332 are engaged by a holding bar 343 (Fig. 2). This bar extends from side to side of the machine below the shaft 333 and is supported at its opposite ends upon a pair of crank arms 344 which are fixed upon a tubular rock shaft 345, and project forwardly therefrom. The tubular rock shaft 345 is sleeved over a crank shaft 346 which extends from side to side of the machine and has its opposite ends journaled in the side frame 63 and 64. In addition to the forwardly extending crank arms 344, the tubular rock shaft 345 is also provided with a rearwardly extending crank arm 347 (Fig. 3). This last mentioned crank arm is supplied with a cam roller 348 for engagement with a cam 349. The cam 349 is shiftably mounted upon the cam shaft 176. It has a plurality of elevated portions 350, 351, 352 and 353, all of which are provided for engagement with the cam roller 348 to release the holding bar 343 from engagement with the subtraction pinions 332 in the different positions of the cam. In the ordinary operation of the machine, as when the sum of the several items is to appear upon the accumulator wheels 79, the cam 349 occupies the position illustrated in Fig. 3. In this position of the cam, its elevated portion 350 is engaged with the cam roller 348 during the latter part of each rotation of the cam shaft 176. The holding bar 343 is there-

by released from engagement with the subtraction pinions 332 to permit the rotation of the accumulator wheels 79 by the pawls 142 only during the return movement of the wheel segments 128 to 135^a. 70

In the event an item is to be subtracted, the subtraction wheels 332 are shifted into the path of movement of the pawls 142 of the corresponding wheel segments 128 to 135^a and the pawls are depressed as they pass the accumulator wheels 79, during the return movement of the wheel segments. This depression of the pawls 142 is accomplished through the use of a plurality of shoes 354 (Fig. 2), one for engaging the rear end portions of the pawls of each of the wheel segments 128 to 135^a. These shoes are supported in alinement upon a bar 355, and they are brought to operative position by moving the bar forwardly. As shown, the bar 355 is carried by a pair of crank arms 356. These crank arms are fixed upon the crank shaft 346, beyond the ends of the tubular rock shaft 345 by which the crank shaft 346 is inclosed throughout the greater portion of its length. An arm 357, formed integral with one of the crank arms 356, extends rearwardly therefrom and carries a cam roller 358 which also cooperates with the cam 349. The cam 349 is provided with two elevated portions 359 and 360 for engaging the cam roller 358 in different positions of the cam. 95

The shifting of the cam 349 on the cam shaft 176 is accomplished by the depression of any one of the controlling keys 95, 96, 97, but in different amounts. For this purpose a shipper bar 361 (Fig. 5), is slidably supported to extend in rear of the stems 102, 103, 104 of said keys. This shipper bar 105 carries three studs 362, 363 and 364, each of which extends into the path of one of three wing cams 356, 366 and 367, which are mounted upon the key stems 102, 103 and 104 respectively. One support for the shipper bar 361 is provided by a gib 368 which connects with an upright part, as 369, of the bracket plate 106. The shipper bar 361 is also supported by being slidably engaged with the side frame 64. The motion of the shipper bar 361 is communicated to the cam 349 by means of a yoke 370. This yoke is formed upon one end of a shipper bar 361 and is engaged with an annular groove 371 formed in the hub of the cam. 110

A latch mechanism is preferably provided for holding any one of the controlling keys 95, 96, 97 which has been depressed, in its lowered position until the operating handle 82 reaches the end of its forward movement. 125 For this purpose a plurality of pawls 372 are provided.

These pawls are rigidly mounted on a rock shaft 373, and are normally advanced by a spring 377 which operates to rotate the 130

shaft in one direction. Each pawl 372 is adapted to enter either one of two notches 374, 375, formed in the stem 102, 103, 104 of one of the controlling keys 95, 96, 97. 5 The rock shaft 373 is supported by being journaled in the upright part 369 of the bracket plate 106 and in a second bracket arm 376 which rises from this plate. For effecting the retraction of pawls at the end 10 of the forward movement of the operating handle 82, the rock shaft 373 is provided with a crank arm 378 and a link 379 extends rearwardly therefrom. The rear end of the link 379 is connected with a swinging arm 380, and a pin 380^a, (Fig. 3) projects laterally from this arm under the gear segment 177. A lug 381 (Fig. 2), formed on the gear segment 177, engages the pin 380^a to swing the arm 380 rearwardly, as the gear 15 segment 177 reaches the limit of its travel. The swinging arm 380 is supported by being pivotally secured against the side frame 64. When the subtraction key 97 is depressed, the cam 349 is shifted to a position in which 20 its elevated portions 353 and 360 are alined with the cam rollers 348 and 358, respectively. The cam 349 accordingly serves to effect the depression of the holding bar 343, and the advance of the shoe 354 during the 25 return movement of the wheel segments 128 to 135^a. The depression of the subtraction key 97 having also served to shift the subtraction wheels 332 to a position in which they are alined with the pawls 142 of the 30 wheel segment 128 to 135^a, each accumulator wheel 79 is rotated in accordance with the movement of the corresponding wheel segment but in a reverse direction with reference to the movement of these wheels when 35 they are directly engaged by the pawls 142. 40 When a total or a sub-total is to be printed against the platens 58, 71 and 72, (or shown at the sight openings 80) none of the numeral keys 83 is depressed. The movement 45 of the wheel segments 128 to 135^a is accordingly accomplished, not by the engagement of the actuating arm 148 with the pins 141, but by the "clearing" of the accumulator wheels 79, as these wheels are 50 rotated to positions in which they display zeros at the sight openings 81. The "clearing" of the accumulator wheels 79 is accomplished by the engagement of a gear segment 382 (Fig. 4) with a gear 383 which is 55 fixed upon the shaft 277. The gear segment 382 is formed upon a crank arm 384 which rotates with the shaft 136, as by being formed integral with one of the crank arms, as 161 upon which the actuating arm 148 60 is mounted. The gear 383 is so positioned on the shaft 277 as to be normally out of alinement with the gear segment 382. Provision is accordingly made for imparting an 65 endwise movement to the shaft 277 when a total or a subtotal is to be printed. For

this purpose, the hub of the gear 383 is provided with an annular groove 385 and one of the crank arms, as 386, of a rock shaft 387 is engaged with this groove. The rock shaft 387 is supported by being extended longitudinally through a part of the side frame 64. Another crank arm, as 388, of the rock shaft 387 extends into the path of studs 389 and 390 which are carried by the stems 102 and 103 of the total and sub- 70 total keys 95, 96, respectively. 75

At each engagement of the gear 383 with the gear segment 382, the shaft 277 is rotated only through a sufficient distance to bring one of the zero characters of each of the 80 accumulator wheels 79 into register with the corresponding sight opening 81. This motion of the shaft 277 is communicated to the several accumulator wheels by providing the shaft with pins 391 (Fig. 5) which come 85 into engagement with studs, as 392, fixed in the accumulator wheels during the rotation of the shaft. The endwise movement of the shaft 277 to the right, as viewed in Fig. 5, is preferably accomplished by a spring, as 90 393. This spring is shown as being coiled about the shaft and reacting between the hub of one of the accumulator wheels 79 and a disk 394 serves to carry the pins 391 which engage the studs 392 of the adjacent ac- 95 cumulator wheel.

When a "total" is printed, the accumulator wheels 79 are allowed to remain in the "cleared" position. It is accordingly provided that the pawls 142 of the wheel segments 128 to 135^a, are depressed, as they pass the corresponding accumulator wheels, during the return movement of the wheel segments. For this purpose, the wing cam 365 (Fig. 5) serves to shift the cam 349 to a 105 position in which its elevated portion 359 (Fig. 3) is alined with the cam roller 358 for advancing the shoes 354 (Fig. 2) during the latter part of the rotation of the cam. In this operation of the machine, the rotation of the accumulator wheels 79 occurs 110 during the downward movement of the gear segment 382 (Fig. 4) and is not thereafter to be permitted. The cam roller 358 (Fig. 3) is accordingly engaged by an elevated 115 portion 352 of the cam 349 for depressing the holder bar 343 only during the early part of the rotation of the cam.

When a "subtotal" is to be printed, the accumulator wheels 79 are "cleared" by the 120 engagement of the gear 383 with the gear segment 382 (Fig. 4), in the same manner as when a "total" is to be printed, but in this operation the accumulator wheels are to be returned to their original position during 125 the return movement of the wheel segments 128 to 135^a. The wing cam 366 (Fig. 5) which is depressed by the depression of the subtotal key 96, accordingly serves to shift the cam 349 (Fig. 3) only to a position in 130

which the elevated portion 351 of the cam is aligned with the cam roller 348. The elevated portion 351 extends almost entirely around the cam 349 and thereby serves to 5 depress the holder bar 343 to permit the rotation of the accumulator wheels 79 throughout substantially the whole period of rotation of the cam. As this operation does not require the depression of the pawls 10 142, as they pass the accumulator wheels 79, during the return movement of the wheel segments 128 to 135^a, the cam 349 is not provided with any elevated portion for engaging the cam roller 358 when occupying that 15 position to which it is moved by the wing cam 366 (Fig. 5) of the sub-total key. The rigid connection of all of the pawls 372 with the shaft 373 provides that if one of the controlling keys 95, 96 or 97 is improperly depressed its restoration will be permitted by 20 the depression of another one of said keys.

I claim as my invention,—

1. In a calculating machine, in combination, an oscillatable number positioning 25 member, a set of numbers positioned thereby, an accumulator, driving means positively operable upon the number positioning member to move it through variable distances, other driving means operable upon the actuating 30 cumulator for moving it to a definite position and connection between the number positioning member and the accumulator operable to communicate motion from either one of said parts to the other.

35 2. In a calculating machine, in combination, a number positioning wheel, a set of numbers positioned thereby, an accumulator wheel, driving means positively operable upon the number positioning wheel for turning it through variable angular distances in one direction, means for turning the number positioning wheel through like distances in the other direction, other driving means operable upon the accumulator wheel for turning 40 it to a definite angular position and connection between the said two wheels operable to communicate motion from the accumulator wheel to the number positioning wheel and from the number positioning wheel to 45 the accumulator wheel in one direction only.

50 3. In a calculating machine, in combination, a number positioning wheel, a set of numbers positioned thereby, an accumulator wheel, means for oscillating the number positioning wheel, connection between said wheels positively operable for communicating motion from one to the other in one direction but yielding when the number positioning wheel is moved in the other direction 55 by the said oscillating means, and driving means for reversely turning the accumulator wheel with reference to the direction in which it is turned by the means for oscillating the number positioning wheel.

4. In a calculating machine, in combination, an oscillating number positioning wheel, a set of numbers positioned thereby, an accumulator wheel, driving means positively operable upon the number positioning wheel for advancing the number positioning 65 wheel, means for returning the number positioning wheel, connection between said wheels operable only to communicate motion from the number positioning wheel to the accumulator wheel during the return movement of the number positioning wheel and from the accumulator wheel to the number positioning wheel for advancing the number positioning wheel, and other driving means operable upon the accumulator wheel for 70 turning the same in the direction for advancing the number positioning wheel. 75

5. In a calculating machine, in combination, an oscillating number positioning wheel, a set of numbers positioned thereby, 80 an accumulator wheel, driving means positively operable upon the number positioning wheel for advancing the number positioning wheel, means for returning the number positioning wheel, connection between said 85 wheels operable only to communicate motion from the number positioning wheel to the accumulator wheel during the return movement of the number positioning wheel and from the accumulator wheel to the number 90 positioning wheel for advancing the number positioning wheel, other driving means operable upon the accumulator wheel for turning the same in the direction for advancing the number positioning wheel. 95

100 6. In a calculating machine, in combination, a movable type selecting member, a fixed stop located adjacent the path of movement of said type selecting member, an actuating member movable toward the stop, 110 and a set of studs carried by the said type selecting member and movable thereon to enter the path of movement of the actuating member at different distances from the stop. 105

115 7. In a calculating machine, in combination, a movable set of number characters, means for moving the set of number characters in variable amounts and for restoring the set of number characters after each movement, means upon which the restoring movements of the set of number characters are accumulated, means for restoring the accumulating means, means for transmitting the restoring movement of the accumulating means to the said set of number characters, 120 and means for interrupting the transmission of the restoring movement of the said set of number characters to the accumulating 125

means after the movement of the said set of number characters by the restoration of the accumulating means.

8. In a calculating machine, in combination, a row of oscillatable gear members, a set of number characters moved by the oscillations of each of said gear members, unitary driving means for advancing all of the said gear members simultaneously but in variable amounts, means for restoring the said gear members successively from one end of the row, an accumulator wheel rotated by each of the said gear members upon its return movement only and carrying mechanism 10 acting between adjacent accumulator wheels.

9. In a calculating machine, in combination, a pair of type characters, a pair of movable members arranged side by side and each controlling the printing from one of the said type characters, a leaf carried by one of the movable members and extending in front of the other but spaced apart therefrom, a movable filler block normally occupying the space between the last mentioned 25 one of the said movable members and the leaf and means for withdrawing the filler block.

10. In a calculating machine, in combination, a plurality of coaxially mounted wheel segments, a set of number characters, a set of gear teeth yielding to movements in one direction and a set of radially movable pins carried by each wheel segment, the said number characters, gear teeth and movable pins upon each wheel segment being extended over different parts of its rim, a fixed stop rod extending under the rims of all of the wheel segments, an actuating arm extending through all of the wheel segments 30 in front of the said stop rod, means for selectively depressing pins upon the several wheel segments to project between the stop rod and the actuating arm, and a set of accumulator wheels each meshing with the said gear teeth upon one of the wheel segments.

11. In a calculating machine, in combination, an oscillating number wheel, an accumulator wheel, driving means for advancing the number wheel, means for returning the number wheel, connection between said wheels operable only to communicate motion from the number wheel to the accumulator wheel during the return movement of the number wheel and from the accumulator wheel to the number wheel for advancing the number wheel, driving means operable upon the accumulator wheel for turning the same in the direction for advancing the 55 number wheel, and means for releasing the said connection between the wheels operable to permit the return movement of the number wheel without turning the accumulator wheel.

12. In a calculating machine, in combination, a movable set of number characters, means for moving the set of number characters in variable amounts and for restoring the set of number characters after each movement, means upon which the restoring movements of the set of number characters are accumulated, means for restoring the accumulating means, means for transmitting the restoring movement of the accumulating means to the said set of number characters, and means for interrupting the transmission of the restoring movement of the said set of number characters to the accumulating means. 65 70 75

13. In a calculating machine, in combination, a set of movable number characters, a second set of movable number characters upon which a plurality of successive movements of the number characters of the first-mentioned set are accumulated, restoring means operable upon the number characters of the second-mentioned set for returning them after movement to predetermined positions, means for transmitting the said return movements of the number characters of the second-mentioned set to the number characters of the first-mentioned set, restoring means operable upon the number characters of the first-mentioned set to return them after movement to predetermined positions, and actuating means operable successively at a single movement upon the last-mentioned restoring means and upon the number characters of the first-mentioned set in the order named. 80 85 90 95 100

14. In a calculating machine, in combination, a set of movable number characters, a second set of movable number characters upon which a plurality of successive movements of the number characters of the first-mentioned set are accumulated, restoring means operable upon the number characters of the second-mentioned set for returning them after movement to predetermined positions, means for transmitting the said return movements of the number characters of the second-mentioned set to the number characters of the first-mentioned set, restoring means operable upon the number characters of the first-mentioned set to return them after movement to predetermined positions, and actuating means operable successively at a single movement upon the last-mentioned restoring means and upon the first mentioned restoring means in the order named. 105 110 115 120

15. In a calculating machine, in combination, a set of movable number characters, a second set of movable number characters upon which a plurality of successive movements of the number characters of the first-mentioned set are accumulated, restoring means operable upon the number characters 125

- ters of the second-mentioned set for returning them after movement to predetermined positions, means for transmitting the said return movements of the number characters 5 of the second-mentioned set to the number characters of the first-mentioned set, restoring means operable upon the number characters of the first-mentioned set to return them after movement to predetermined positions, and actuating means selectively operable successively at a single movement either upon the last-mentioned restoring means and upon the number characters of the first-mentioned set in the order named 15 or upon the last-mentioned restoring means and upon the first mentioned restoring means in the order named.
16. In a calculating machine, in combination, an oscillatable gear member having 20 yielding gear teeth; a set of number characters moved by the oscillations of said gear member, an accumulator gear engaged with the first-mentioned gear member, an intermediate gear engaged with the accumulator 25 gear and movable into and out of engagement with the first-mentioned gear member, and means for depressing the gear teeth of the first-mentioned gear member in line with the accumulator gear when the intermediate 30 gear is engaged with the first-mentioned gear member.
17. In a calculating machine, in combination, a number printing wheel, an accumulator wheel, connection between said two 35 wheels operable to turn the number printing wheel in one direction by movement of the accumulator wheel in a given direction and to turn the accumulator wheel by movement of the number printing wheel in the reverse 40 direction, driving means operable upon the accumulator wheel for turning it in the said given direction, and other driving means operable upon the number printing wheel for turning it in the said reverse direction after it has been turned by the said 45 turning of the accumulator wheel and while it is connected with the accumulator wheel.
18. In a calculating machine, in combination, a number printing wheel, an accumulator 50 wheel, connection between said two wheels operable to turn the number printing wheel in one direction by movement of the accumulator wheel in a given direction and to turn the accumulator wheel by movement 55 of the number printing wheel in the reverse direction, driving means operable upon the accumulator wheel for turning it in the said given direction, other driving means operable upon the number printing wheel 60 for turning it in the said reverse direction after it has been turned by the said turning of the accumulator wheel, and means for interrupting the connection between the said two wheels during the turning of the num- 65 ber printing wheel by the second mentioned driving means.
19. In a calculating machine, in combination, a number printing wheel, an accumulator wheel, connection between said two 70 wheels operable to turn the number printing wheel in one direction by movement of the accumulator wheel in a given direction and to turn the accumulator wheel by movement of the number printing wheel in the reverse direction, driving means operable upon the accumulator wheel for turning it in the said given direction, other driving means operable upon the number printing wheel for turning it in the said reverse direction after it has been turned by the said 75 turning of the accumulator wheel, and independently controlled means for interrupting the connection between the said two wheels during the turning of the number printing wheel by the second mentioned 80 driving means.
20. In a calculating machine, in combination, a movable set of number characters, driving means positively operable upon the set of number characters for moving them 85 in variable amounts, means for restoring the set of number characters after each movement, means upon which the restoring movements of the set of number characters are accumulated, other driving means for restoring the accumulating means, means for transmitting the restoring movement of the accumulating means to the said set of number characters, and independently controlled means for interrupting the transmission of the restoring movement of the said set of number characters to the accumulating means after the movement of the said set of number characters by the restoration 90 of the accumulating means.
21. In a calculating machine, in combination, an oscillating number positioning member, a set of numbers positioned thereby, driving means positively operable upon the number positioning member, an accumulator, other driving means operable to clear the accumulator, and connection between the number positioning member and the accumulator operable to actuate the accumulator by the movement of the number positioning member when the number positioning member is moved in one direction only and to move the number positioning member by the said clearing of the accumulator.
22. In a calculating machine, in combination, an oscillating number positioning member, a set of numbers positioned thereby, driving means positively operable upon the number positioning member, an accumulator, other driving means operable to clear the accumulator, and connection between the number positioning member and the accumulator operable to actuate the accumulator in

either direction by the movement of the number positioning member when the number positioning member is moved in one direction only and to move the number positioning member by the said clearing of the accumulator.

23. In a calculating machine, in combination, an oscillating number positioning member, a set of numbers positioned thereby, 10 driving means positively operable upon the number positioning member, an accumulator, other driving means operable to clear the accumulator, connection between the number positioning member and the accumulator operable to actuate the accumulator by the movement of the number positioning member when the number positioning member is moved in one direction only and to move the number positioning member by the 15 said clearing of the accumulator, and means for interrupting the said connection between the number positioning member and the accumulator during the movement of the number positioning member next following the 20 said clearing of the accumulator.

24. In a calculating machine, in combination, a set of visible number wheels, a set 30 of movable positioning members operable upon the number wheels to show different numbers in accordance with the amount of movement permitted in the positioning members, a set of keys and an accumulator selectively operable to control the movements of the said positioning members, the 35 accumulator being actuated by the positioning members when their movement is controlled by the keys, restoring means operable upon the visible number wheels and an actuating device operable successively at 40 each movement upon the restoring means and the said movable positioning members in the order named.

25. In a calculating machine, in combination, a set of number printing type, type 45 setting means, a set of keys and an accumulator selectively operable to control the type setting means for arranging the type to print either a selected number or a number representing the sum of the numbers printed 50 from a plurality of previous operations of the type setting means, a set of visible number characters, means for positioning the visible number characters to show the same number which the type is set to print 55 whether the setting of the type is controlled by the set of keys or by the accumulator, means for restoring the visible number characters, and actuating means operable successively at each movement upon the said 60 restoring means and upon the type setting means in the order named.

26. In a calculating machine, in combination, an oscillatable number positioning member, a set of numbers positioned there-

by, an accumulator, driving means positively operable upon the number positioning member to move it through variable distances, other driving means operable upon the accumulator to move it to a definite position, and connection between the number 65 positioning member and the accumulator operable to communicate motion from either one of said parts to the other.

27. In a calculating machine, in combination, a set of visible number wheels, a set 70 of movable positioning members operable upon the number wheels to show different numbers in accordance with the amount of movement of the positioning members, an 75 accumulator, driving means operable upon the number positioning members to return them after movement to predetermined positions, other driving means directly operable upon the accumulator to clear the same, and connection between the said movable 80 positioning members and the accumulator operable to transmit movement from the said positioning members to the accumulator during the said return movement of the said 85 positioning members by the first mentioned 90 driving means and from the accumulator to the said positioning members during the said clearing of the accumulator.

28. In a calculating machine, in combination, a movable set of number characters, 95 means for moving the set of number characters in variable amounts and for restoring the set of number characters after each movement, means upon which the restoring movements of the set of number characters 100 are accumulated, means for restoring the accumulating means, and means for transmitting the restoring movement of the accumulating means to the said set of number characters.

29. In a calculating machine, in combination, a movable set of number characters, means positively operable upon the set of number characters for moving them in variable amounts, means for restoring the set 110 of number characters after each movement, means upon which the restoring movements of the set of number characters are accumulated, means for restoring the accumulating means and means for transmitting the restoring movements of the accumulating means to the said set of number characters.

30. In a calculating machine, in combination, a movable set of number characters, means positively operable upon the set of 115 number characters for moving them in variable amounts, means for restoring the set of number characters after each movement, means upon which the restoring movements of the set of number characters are accumulated, means for restoring the accumulating means, means for transmitting the restoring movements of the accumulating means.

- to the said set of number characters, and means for interrupting the transmission of the restoring movement of the said set of number characters to the accumulating means. 5
31. In a calculating machine, in combination, a movable number positioning member, a set of numbers positioned thereby, means for oscillating the number positioning member, an accumulator, connection between the movable number positioning member and the accumulator wheel positively operable for communicating motion from either one of said parts to the other in one direction but yielding when the number positioning member is moved in the other direction by the said oscillating means and driving means for reversely turning the accumulator wheel with reference to the direction in 10 which it is turned by the means for oscillating the number positioning member. 15
32. In a calculating machine, in combination, a movable number positioning member, a set of numbers positioned thereby, means for oscillating the number positioning member, an accumulator, connection between the movable number positioning member and the accumulator wheel positively operable for communicating motion 20 from either one of said parts to the other in one direction but yielding when the number positioning member is moved in the other direction by the said oscillating means, driving means for reversely turning the accumulator wheel with reference to the direction in 25 which it is turned by the means for oscillating the number positioning member and means for releasing the said connection between the movable number positioning 30 member and the accumulator wheel during the movement of the number positioning member by the said oscillating means next following its movement by the said driving means for reversely turning the accumulator 35 wheel. 40
33. In a calculating machine, in combination, an oscillatable number positioning rack having movable teeth, a set of numbers positioned by movement of the rack and means acting to retract the rack teeth during movement of the rack in one direction. 45
34. In a calculating machine, in combination, a set of number printing type, a set of keys and an accumulator selectively operable to control the setting of the type for printing either a selected number or a number representing the sum of the numbers printed from a plurality of previous settings of the type, means for restoring the number printing type, a set of visible number characters positioned by the restoring movement of the printing type, and means automatically operable to restore the said visible 50 numbers. 55
35. In a calculating machine, in combination, type setting and restoring means, a set of number printing type positioned thereby, a set of keys and an accumulator selectively operable to control the type setting and restoring means for setting the type to print either a selected number or the sum of the numbers printed from a plurality of previous settings of the type, and a visible set of number wheels positioned by the type setting 60 and restoring means to show the same number which the type is set to print after the type setting and restoring means has completed its movement and means automatically operable to clear the set of visible number wheels before the next movement of the type setting and restoring means. 65
36. The combination with the gear racks of a calculating machine, of a set of keys operable to control the movement of the racks in accordance with a selected number, a set of number wheels actuated by the racks to show the said selected number after the racks have completed their movement and means automatically operable to clear the set of number wheels before the next actuation of the said set of number wheels by the racks. 70
37. The combination with the gear racks of a calculating machine, of a set of keys and an accumulator selectively operable to control the movement of the racks either in accordance with a selected number or a number which is the sum of the numbers corresponding with a plurality of previous settings of the keys, a set of number wheels actuated by the racks to show the number which corresponds with the amount of movement of the racks after the movement of the racks has been completed and means automatically operable to clear the set of number wheels before the next actuation of the number wheels by the racks. 75
38. In a calculating machine, in combination, an oscillatable number positioning member, a set of numbers positioned thereby, an accumulator, driving means positively operable upon the number positioning member to move it through variable distances, other driving means positively operable upon the accumulator to move it to a definite position, and connection between the number positioning member and the accumulator operable to communicate motion from either one of said parts to the other. 80
39. In a calculating machine, in combination, an oscillating number positioning rack having movable teeth, a number wheel having gear teeth meshing with the rack teeth when advanced and means for retracting the rack teeth. 85

WILLIAM J. FABIAN.
